UNITED STATES PATENT OFFICE

HERBERT GLASER, OF NEW YORK, N. Y.

LOCK

Application filed December 10, 1928. Serial No. 324,845.

This invention relates to an improvement in a lock primarily intended for use in connection with elevators. It has for its object the provision of such a lock which shall be 5 of simple, sturdy construction yet extremely efficient and durable in operation.

The primary object therefore, of the invention is to provide a lock of the character mentioned which shall not only act as a lock 10 for an elevator shaft door but which will also act as a switch for the elevator-operating circuit so that operation of the elevator while the shaft door is open will be impossible.

15 A further object of the invention is to provide a lock for elevator shaft doors in which the lock is capable of attachment to the door frame in several ways to accommodate both swinging and sliding doors or to accommodate the position in which an operating cam 20 may most suitably be attached to the elevator.

A further object of my invention is to 25 provide a combined lock and switch in which I utilize a novel form of circuit-closing device which is not only capable of long wear and use without adjustment, but which makes a wiping contact thus assuring positive electrical contact between the switch elements which it serves to connect.

With these objects and such other objects as may hereinafter appear, in view, I have devised the particular arrangement of parts hereinafter set forth and more particularly 35 pointed out in the claims appended hereto.

Reference is to be had to the accompanying drawing, forming a part hereof in which Figure 1 is a front elevation of my improved lock with the cover plate removed 40 to disclose construction;

Figure 2 is a sectional view on the line 2—2 of Figure 1, looking in the direction of the arrows;

Figure 3 is a sectional view on the line 45 3—3 of Figure 1, looking in the direction of the arrows;

Figure 4 is a sectional view on the line 4—4 of Figure 1 looking in the direction of the arrows;

50 Figure 5 is a sectional view similar to that

shown in Figure 3, except that the actuating rod is shown positioned at right angles to its position in Figure 3;

Figure 6 is a sectional view of a portion of an elevator shaft and door and diagrammatically illustrating the position of the lock and its attendant parts when a swinging type of door is used;

Figure 7 is a similar view showing the position of the lock and attendant parts when a sliding door is employed;

Figure 8 is a sectional view on the line 8—8 of Figure 6, looking in the direction of the arrows;

Figure 9 is a plan view of the lock member and circuit-closing device with a portion of the same being broken away to disclose construction; and

Figure 10 is a transverse sectional view across the circuit-closing device forming a 70 part of the structure shown in Figure 9.

Throughout the various views of the drawings, similar reference characters designate similar parts.

In the embodiment of my invention disclosed in the accompanying drawing, 1 indicates the casing in which my improved lock mechanism is contained. The same may be made of any suitable metal and is preferably rectangular in form and substantially shallow in depth. At 2 is shown a cover plate which serves to close the casing 1 and keep the mechanism clean and free from dirt and dust. It also prevents unauthorized persons from tampering with the mechanism contained within the casing.

At 3 and 4 is shown a pair of electrical contact screws which secure in position a pair of contact members 5 and 6. Each of these contact members 5 and 6 comprises a strip of metal having a base portion 7 and an upwardly inclined tongue portion 8 having a rounded or curved outer surface against which a circuit-closing member is adapted to resiliently abut. These contacts 5 and 6 are mounted upon a strip of insulation 9 which is secured to the base plate 10 of the casing 1 by suitable screws 11. The electrical circuit for operating the elevator is connected to the two contacts 5 and 6 by 100

means of wiring, a part of which is shown at 12 and 13, which wiring may enter into the casing 1 through any suitable openings provided therein for the purpose. Since the contacts 5 and 6 are spaced away from one another, it will be obvious that the same have to be electrically connected by a suitable conductor to close the circuit between the wires 12 and 13 to permit operation of the elevator. A suitable circuit-closing member for this purpose is provided, the same now being described.

The side walls 14 and 15 of the casing 1 are provided with a pair of bosses 16 and 17 in which is mounted a pivot pin 18 which supports a rocking lever 19. This lever 19 is provided with a boss 20 through which the pivot pin 18 passes, the boss being capable of a rocking or oscillating movement on said pin as will be described.

The lever 19 is provided with an integrally formed downwardly extending finger 20' which acts as a latch member for the elevator shaft door. The lever 19 is also provided with an upwardly extending arm portion 21 to which is secured a hollow casing 22, this casing being secured in place on the arm 21 by a pair of screws 23.

At 24 is shown a plunger member in the form of a block of insulation which is provided with a centrally located bore 25 in which a coil spring 26 is seated. The coil spring 26 abuts against the rear surface 27 of the part 21 of the rocking lever and normally tends to thrust the insulated block 24 out of the casing 22.

The block 24 is restricted in its outward movement by means of the pins 23 which pass through apertures 28 formed in the insulated block 22. The apertures 28 are sufficiently enlarged to permit the block to have a fair degree of lateral movement or play within the tubular casing 22 so that the contact member just described is self aligning.

To the outer end of the block 24 is secured a circuit-closing member in the form of a half-round metallic strip 29, the same being held in position by a countersunk screw 30 which threads into the end of the block 24.

Through the structure just described, it will be seen that the contact-closing device provided normally extends across and is caused to resiliently bear against to electrically connect the two contacts 5 and 6, thus maintaining a closed circuit.

By means of mechanism to be described, it will be seen that the lever 19 is caused to move with an oscillating movement about its pivot 18 to swing the contact member 29 outwardly toward the cover plate 2, to break the circuit between the contact members 5 and 6.

65 A coil spring 31 bearing against the base

plate 10 of the casing 1 enters into a recess in the finger 20 and normally tends to hold the circuit-closing member 29 in the position shown in Figures 1 and 2 so that the circuit between the contact members 5 and 6 is normally kept closed.

At 32 is shown a plate which is secured to the elevator shaft door 65 (Figure 6) in a manner to be hereinafter described. Extending from the face of this plate is a hook shaped lock member 33 and a circuit-closing member 34. The circuit closing member 34 consists of a lug 35 formed integral with the plate 33 and extending outwardly therefrom, and an insulating strip 36 secured to the ear 35 by screws 37. At the outer end of the insulating strip 36 is secured a rounded metallic contact-making strip 38. When the door 65 is closed, the hook shaped member 33 enters into the casing 1 through an opening 39 provided in the side plate 15 of said casing and forms a hooked engagement about the latch member 20. Simultaneously with this engagement, the circuit closing member 38 abuts against 90 and closes an electrical circuit between two flexible contacts 40 and 41.

Each of these contacts 40 and 41 is pivotally mounted at 42 in a pair of ears 43 and 44, these ears being mounted upon a strip of insulation 45, secured to the end plate 46 of the casing by suitable fastening screws 47.

To prevent arcing between the two pairs of ears 43 and 44 and the contacts carried thereby, I provide an insulating rib or wall 49 between them. The contact members 40 and 41 are resiliently maintained in a substantially upright position when not under pressure of the circuit-closing member 38, by coil springs 50. Stops 50' are provided to limit the movement of these contact members in one direction.

The wiring of an electric circuit for operating a torque motor which operates a retiring cam secured to the elevator, is connected to the contacts 51 and 52 as shown at 53 and 54. Thus when the circuit-closing member 38 abuts against the contacts 40 and 41, it acts to electrically connect the same and closes the circuit for operating the torque motor heretofore mentioned.

The boss 17 which is formed as part of the casing 1, is provided with a bore 55 extending through it at right angles to the bore in which the pin 18 is fitted and an oscillating rod or shaft 56 is mounted in said bore 55 to freely move therein. A portion of the rod 56 extends out beyond the back plate 10 of the casing and such projecting part is provided with a lever 57 on which is rotatably mounted a roller 58. The inner end of the shaft or rod 56 is located within the casing and the same is provided with a finger 59 terminating in a ball-

shaped end 60. This ball shaped end 60 exerts pressure on a projecting lug 61 provided on the boss 20 of the lever 19 to rock the lever about its axis 18 to break the circuit between the contacts 5 and 6 and to free 5 the latch member 20' from its engagement with the hook 33. The rod 56 is provided with a suitable positioning stop in the form of a pin 85 and washer 86.

10 Through the construction just described, it will be seen that when the lever 57 fixed on the rod 56 is swung toward the right in Figure 1, the finger 59 is depressed, the ball shaped end of the same exerting pressure 15 upon the lug 61, causing the rocking lever 19 to be swung about its axis 18 against the pressure of the spring 31, so that the finger 20' is swung inwardly toward the rear plate 10 and caused to free itself from its engagement with the hook-shaped lock member 33. By this rocking action of the lever 19 the 20 circuit-closing member 29 is simultaneously swung outwardly toward the plate 2 to open the circuit previously closed across the contacts 5 and 6. When pressure against the 25 roller 58 is removed, the same swings back to its former position under the impulse of the spring 31 and restores the parts to the position disclosed in Figures 1 and 2. The lever 30 19 is provided with a stop 62 that abuts against a fixed projection 63 extending inwardly from the inner face of the rear plate 10 of the casing.

From the foregoing, the operation of my 35 improved lock will be readily understood. In Figure 6, I have shown the same as applied to an elevator shaft door opening, on which a swinging door is utilized. Here the door is shown at 65, the same being hinged 40 at 66 to a door frame 67. The casing 1 containing the lock mechanism, is secured to the side of the door frame located opposite to the hinge 66 of the door, in the position substantially as shown in Figure 6. When a 45 swinging door of the type shown in Figure 6 is utilized, the plate 32 is secured to the face of the door and the casing 1 so secured to the door frame that when the door is closed, the plate will fit over and close the 50 opening 39 in the casing 1 and thus project the hooked lock member 33 and circuit-closing member 38 into the casing in the manner disclosed in Figure 1.

At 68 is shown a portion of the elevator. 55 The same carries a suitable plate 69 so located that a cam carried by said plate will act to operate against the roller 58 to unlock the door when the elevator is aligned with the door opening. The plate 69 carries a 60 retiring cam or shoe 70 which is pivotally connected at 71 and 72 to a pair of parallel links 73 which are in turn pivoted to the plate 69 as at 74 and 75. A chain, cord or 65 other flexible member 76 is secured to the

cam 70 and the same passes over a roller 77 from whence it passes over a series of other rollers not shown, and finally to a torque motor heretofore mentioned. The torque motor is operated by an electrical circuit 70 of which the wires 53 and 54 form a part. The motor is so wired that during the operation of raising or lowering the elevator, said motor acts to exert a pull upon the chain or cord 76 to hold the cam 70 in its 75 raised position and out of contact with the roller 58. With the stopping of the elevator at a floor, the torque motor just mentioned ceases its operation and consequently its pull upon the flexible member 76, permitting the 80 cam 70 to descend by gravity to its lowered position shown in Figure 8, its descent being limited by a suitable stop 78. While in this lowered position, the cam 70 is properly located to strike the roller 58, thus causing the 85 lever 57 on which said roller is secured, to swing to the right, in Figure 1, and act to pivot the lever 19 about its axis 18 so that the finger 20' swings inwardly toward the plate 10 of the casing, to free itself of engagement with the hook shaped lock member 33. Simultaneously, the circuit-closing member 29 is swung outwardly toward the plate 2 to open the connection between the contacts 4 and 5. In other words, when the 90 elevator reaches a floor and stops at said floor, the cam 70 becomes operative to swing the lever 20' inwardly as was heretofore described to free the lock member 33 so that the door 65 may be manually opened.

It will be seen that, as was heretofore mentioned, the elevator operating circuit, extending through the contacts 5 and 6 is by this operation, simultaneously opened. Thus, while the elevator door 65 is open, it 100 is impossible to operate the elevator. Simultaneously with the opening of the door, the circuit-closing member 38 carried by the door is moved out of engagement with the contact members 40 and 41, with the result 105 that the torque motor circuit between said members 40 and 41 is opened. Thus, it is impossible for the torque motor to operate and independently act to raise the cam 70 and accidentally permit closing of the circuit across the contacts 5 and 6 while the door is open. When the door is closed, it 110 will be seen that circuit is again made across the contacts 40 and 41, permitting immediate operation of the torque motor heretofore 115 mentioned, which immediately acts to raise the cam 70 which releases its pressure on the roller 58, permitting said roller and its attached lever 57 to swing back to its normal or closed position disclosed in Figure 1, causing the elevator operating circuit to be closed across the contacts 5 and 6 by the circuit-closing member 29, and the latch finger 20' to be swung forward toward the 120 plate 2 to engage with the hook shaped lock 125 member 33.

member 33 to hold the door in locked position.

In the structure shown in Figures 5 and 7, the operation of the device is similar in all respects to that just described except that a sliding door 90 rather than a swinging door is utilized, and the operating rod 56 is located in a position at right angles to that shown in Figures 1, 2, 3 and 6. In the structure shown in Figures 5 and 7, the rod 56^a is used to form a pivotal support for the lever 19, the same being fixedly secured and rocking with the boss 20 formed on said lever by means of set screws 80. In this structure, the operating rod or shaft 56^a is at right angles to its former position described with respect to Figures 1, 2, 3 and 6, said lever 56^a being in the structure just described directly fixed to the lever 19 by the set screws 80.

It will be seen that in the structure described, a substantial and sturdy arrangement of the parts is provided without resorting to a complex arrangement likely to be rendered inoperative by wear or otherwise. Through the utilization of resilient self-aligning electrical contacts such as is herein described, a wiping, self-cleaning electrical contact between the parts is provided.

While I have shown the circuit-closing member 38 as being fixed and abutting against resiliently mounted contacts, a resilient circuit-closing member such as at 29 may be employed to abut against rigid contacts where such a construction is preferred. This and other embodiments of my invention may be readily made without departing from the spirit of my invention.

What I claim is:—

1. In an elevator door lock, two pairs of terminals, an elevator shaft door carrying a circuit-closing device adapted to connect the terminals of one pair, a rocking member having a pair of oppositely disposed arms, one of said arms carrying a resilient circuit-closing member adapted to connect the terminals of the other pair, a projection on the elevator shaft door adapted to engage with the other arm when the door is in its closed position, a shaft for oscillating the rocking member and means carried by an elevator for oscillating said shaft.

2. In an elevator shaft door lock, an elevator operating circuit having a pair of spaced terminals provided with inclined faces, a circuit-closing member adapted to oscillate about a pivot, said circuit-closing member having a tubular body, an insulating spring-pressed plunger member mounted therein, said plunger having an outer metallic terminal adapted to move across the inclined faces of the terminals with a wiping action and establish an electrical connection between the terminals.

3. In a device of the character described,

a casing, a spring-pressed member pivotally mounted therein, a tubular arm carried by said lever, a pair of electric circuit terminals within the casing adjacent to said arm, a spring-pressed plunger within the tubular arm and partly protruding out of the same, a contact member on the protruding end of said plunger adapted to make a wiping contact with said terminals, a finger on said rocking lever, an elevator shaft door having a latch member adapted to enter the casing and engage with said finger, a circuit-closing member carried by said door, a pair of electric circuit terminals within the casing and in the path of movement of the door-carried circuit-closing member, an oscillating shaft for moving the rocking member against the tension of its spring, and cam means carried by an elevator for moving said oscillating shaft.

4. In an elevator shaft door lock, a pair of spaced terminals connected in circuit with an elevator-operating means, means for closing said circuit across said terminals comprising a rocker member provided with a contact, an elevator shaft door carrying a protruding lock member adapted to engage with a portion of said rocker member when contact is established across said terminals, an elevator having a movable cam, electric means for operating said cam, a pair of terminals in circuit with said cam-operating means, and circuit-closing means carried by the door for closing circuit between the last mentioned terminals when the door is in its closed position.

5. In an elevator door lock, a casing having a back plate and spaced side walls, a rocking shaft pivoted between said side walls, an oscillating member on said shaft, said member having a tubular arm, a contact-making member resiliently mounted in and projecting out of the end of said arm, a pair of contacts secured on the back wall of the casing, said contacts being adapted to be bridged by the contact-making member when the arm in which the same is mounted is moved about its axis toward the rear wall of the casing, a locking arm projecting from the oscillatory member adapted to engage with a door latch when said arm is thrust away from the rear wall of the casing, and resilient means disposed between the rear wall of the casing and said locking arm for normally forcing said arm away from said rear wall and in engagement with the door latch.

6. In an elevator door lock, a movable member provided with means for closing an elevator-operating electric circuit, an elevator door carrying a latch member and a circuit-closing member, locking means on the movable member for engaging with the latch member co-incidently with the closing of the elevator-operating circuit, cam means car-

ried by an elevator for opening the elevator-operating circuit and simultaneously freeing the elevator door latch from its engagement with the locking means on the movable member, and a pair of contacts wired in the cam-operating circuit, which contacts are adapted to be bridged by the circuit-closing means carried by the door co-incidently with the closing of the elevator-operating circuit.

5 10 Signed at the city, county and State of New York, this 7th day of December, 1928.

HERBERT GLASER.
